UNITED STATES PATENT OFFICE.

ISABELLA GILLEN, OF WOODMERE, NEW YORK.

SHUT-OFF SYSTEM FOR CONDUITS.

1,072,938.

Specification of Letters Patent.

Patented Sept. 9, 1913.

Application filed August 24, 1912. Serial No. 716,842.

To all whom it may concern:

Be it known that I, ISABELLA GILLEN, a citizen of the United States, and a resident of Woodmere, in the county of Nassau and State of New York, have invented a new and Improved Shut-Off System for Conduits, of which the following is a full, clear, and exact description.

My invention relates to improvements for automatically shutting off conduits employed to supply buildings with gas or other fluid agent used for industrial purposes, and it comprises apparatus which is preferably actuated by electricity to operate a valve located in the conduit and close the same when conditions make it desirable that this be done.

The primary object of my invention is to provide a system of the kind mentioned which is especially adapted to be applied to gas mains, so that upon the outbreak of a fire the gas will be automatically shut off, thus preventing explosions in case the gas pipes become damaged and allow their contents to flow freely out into the interior of the burning building.

Reference is to be had to the accompanying drawings forming a part of this specification, in which the same characters of reference indicate the same parts in all the views.

Figure 1 represents a diagrammatic view of a building, showing my system applied to the several floors thereof; Fig. 2 is a view of the actuating device for the shut-off valve; Fig. 3 is a horizontal sectional view on the line 3-3 of Fig. 2; and Fig. 4 is a detail view of a thermally-controlled circuit closer by means of which the parts for operating the shut-off valve are thrown into operation.

On the drawings, 1 represents a building, and 2 a gas supply pipe leading into the cellar of the same. 3 is the meter, and 4 the valve by means of which the flow of gas to the meter is controlled, this valve having a lever to enable it to be actuated by hand when desired.

The shut-off valve for stopping the flow of gas automatically in case a fire breaks out in the building is shown at 5, and this valve is arranged as near to the wall as possible. The valve 5 is controlled by electro-magnetically-actuated devices shown at 6, and these devices are in circuit with conductors 7 which pass through every room or apart-

ment of the building 1 and are supplied with current from a source of electricity shown at 8, this source being in series with the devices 6. The circuit through the source 8 and the devices 6 can be closed by any one of a number of thermally-controlled circuit closers 9, one of which can be arranged on any floor or in any room of the building, so that no matter where the flames may originate the system will work in the manner described.

The shut-off valve 5 is provided with a head 10 which is operated by means of a stem 11 having a cap 12 which fits over the head 10. This stem 11 carries an operating arm 13 which is fixed thereon, and another arm 14 which is loose thereon, these two arms being connected by means of a spiral spring 15 which encircles the stem 11. 75

16 are rods which have collars at their lower ends through which the conduits 2 are passed, these rods being secured to conduits on opposite sides of the valve 5, and they are joined at their upper ends by means of a bridging member 17, being made fast to the bridging member 17 by suitable locking nuts shown in Fig. 2. This member 17 is bent up at one end and supports a magnet 18 which actuates an armature 19, the lower end of which passes through an opening in the bridging piece 17. Normally this armature 19 is in the path of a projection 20 of fusible metal carried by the lever 13, and serves to hold the lever 13 in such position as to keep the valve 5 open. 21 is a plate secured to the top of one of the rods 16 above the bridging piece 17, and having a notch 22 to limit the outward movement of the armature 19, and also to prevent the same from swinging laterally at right-angles to the bridging plate 17. 95

The electro-magnet 18 and the source of current shown at 8 are connected in series by the conductors 7, as described. These conductors 7 lead to every floor or apartment of the building, and each floor or apartment is provided with one of the circuit closers 9 bridged across the conductor 7. Each of the circuit closers 9 comprises a block of insulating material 23 supported in fixed position upon a wall or partition and having recesses 24. 25 are binding posts which extend into the recesses 24; and 26 is a conductor which has a pair of arms, 110 one of which extends into each of the recesses 24, but is normally supported to keep

its arms out of contact with the inner ends of the metallic binding posts 25, shown in Fig. 4. These members 26 are carried by elongated strips 27 which are preferably of metal and stretched taut so as to keep the circuit closers 26 out of contact with the inner ends of the binding posts 25 for all normal temperatures.

The manner of operation of my improved system is as follows: For normal temperatures the conductor 26 will be suspended out of contact with the inner ends of the binding posts 25, and the circuit through the magnet 18 will be opened. Consequently, the armature 19, which is set by hand so as to move its lower end into engagement with the fusible metal block 20, will hold the arm 13 against the tension of the spring 15 and keep the valve 5 opened to permit a free flow of gas through the pipe 2. As soon, however, as a fire breaks out on one of the floors or in one of the rooms of the building, the heat due to the flames will cause the strip 27 to expand. As a result, the conducting member 26 will be lowered to close the circuit across the main lead 7. The magnet 18 will now be actuated, the armature 19 attracted and the arm 13 released. The spring 15 will then move the stem 11 to close the valve and shut off the further flow of gas into the building, as desired. In this way all danger of explosions due to the presence of gas in a burning building, which might take place in case the gas were not shut off, is obviated. It is easy to perceive in case of a fire that the gas pipes can be melted or broken, thus giving rise to leaks, and the danger due to the presence of gas in the burning building and the possibility of damage arising therefrom can be appreciated by any one.

It will be seen that in the fusible block 20 an additional safeguard is provided. As soon as the heat becomes sufficiently intense this block will melt and allow the valve to close under the action of the spring 15, whether the armature is drawn in by the magnet 18 or not. Hence if, for any reason, all of the circuit closers on the different floors of the building should fail to operate, supposing the fire should break out on one of the upper floors, the block 20 when sufficiently heated will release the spring and cause the valve to close before the heat can become intense enough to melt the pipes and give rise to the danger mentioned. This, however, is an unlikely case, as one or more of the circuit closers shown at 9 will be sure to operate in any event as soon as the flames raise the temperature of the building a few degrees above normal.

If desired, I may also arrange a hand switch in each apartment or room to enable the occupants to close the circuit through the magnet a moment a fire is discovered, so as

not to make the safety of the building entirely dependent on the action of the automatic circuit closers 26. Such a switch is shown diagrammatically at 28, bridged across the main leads 7. It may be in the form of a push button switch if preferred. On the lowest floor this switch may be located near the main entrance, so that it can be operated by the firemen as soon as the latter gain access to the building.

I wish to have it understood that my system is not necessarily restricted to gas pipes or the like, but may be applied to almost any conduit that is led into a building, whether used for business or residential purposes, and I desire to have it understood further that the above drawings and description are illustrative only, and that I do not care to be limited to the exact details shown or described, but reserve to myself the right to make such changes in the shape, size and arrangement of the parts as fairly fall within the scope and spirit of my invention.

Having thus described my invention, I claim as new and desire to secure by Letters Patent:

1. In a system of the kind described, the combination of a conduit having a valve therein, uprights supported by the conduit on opposite sides of the valve, a bridge connecting the upper ends of said uprights together, said bridge supporting an electromagnet and a pivoted armature thereon, means for engaging said valve and tending to turn the same to closed position, said means being normally engaged by said armature to hold the valve open, and means susceptible to the action of heat for closing a circuit through said magnet to withdraw the armature and allow the valve to move to close the conduit.

2. The combination of a conduit having a valve therein, uprights supported by the conduit on either side of the valve, a bridge connecting the upper ends of the uprights together, the said bridge having a U-shaped end, a magnet and a movable armature carried by said U-shaped end, means for engaging said valve and moving the same to closed position, said means being normally engaged by the armature to hold the valve open, and means susceptible to the action of heat for closing the circuit through said magnet to withdraw the armature and allow the valve to be moved to close the conduit.

3. In a system of the kind described, the combination of a conduit having a valve therein, uprights supported by the conduit on either side of the valve, a bridge connecting the upper ends of said uprights together, said bridge having a U-shaped end, a magnet and a movable armature carried by said U-shaped end, means for engaging the valve and turning the same, said means being normally engaged by the armature to

hold the valve open, a plate having a notched end carried on the end of one of the uprights to engage the armature and prevent lateral movement thereof, and means susceptible to the action of heat for closing the circuit through said magnet to withdraw the armature and allow the valve to move to close the circuit.

In testimony whereof I have signed my name to this specification in the presence of two subscribing witnesses.

ISABELLA GILLEN.
